(57) CLAIM

The ornamental design for an abdominal roller wheel with support arm exercise device, as shown and described.

DESCRIPTION

FIG. 1 is a perspective view of an abdominal roller wheel with support arm exercise device showing my new design; FIG. 2 is a front view thereof;

FIG. 3 is a back view thereof;

FIG. 4 is a top view thereof;

FIG. 5 is a bottom view thereof;

FIG. 6 is a right-side view thereof; and,

FIG. 7 is a left-side view thereof.

1 Claim, 5 Drawing Sheets
